(57) **CLAIM**

The ornamental design for an electronic device, as shown and described.

DESCRIPTION

FIG. 1 is a perspective view of an electronic device showing the new design;

FIG. 2 is a front view of the electronic device from FIG. 1; FIG. 3 is a back view of the electronic device from FIG. 1; FIG. 4 is a side view of the electronic device from FIG. 1; FIG. 5 is another side view of the electronic device from FIG. 1;

FIG. 6 is a top view of the electronic device from FIG. 1; and, FIG. 7 is a bottom view of the electronic device from FIG. 1. The broken lines shown in the drawings represent portions of the electronic device that form no part of the claimed design.
